[Term of Patent 3½ years.]

To all whom it may concern:

Be it known that I, JOHN HAMER, of England, now residing in the city of Lowell, county of Middlesex and State of Massachusetts, have invented and produced a new and original Design for a Pattern to be inwrought into Two or Three Ply, Ingrain, and other Carpeting, in such colors as may be desired; and I do hereby declare that the photographic print accompanying this specification does give and convey to any one skilled in the art of carpet-weaving a more definite and thorough description of the nature of my invention than it is in the power of language otherwise to convey,

What I claim as my invention, and desire to secure by Letters Patent, is—
